UNITED STATES PATENT OFFICE.

JOHN A. PEER, OF WASHINGTON, DISTRICT OF COLUMBIA.

MILL.

SPECIFICATION forming part of Letters Patent No. 643,273, dated February 13, 1900.

Application filed March 24, 1899. Serial No. 710,345. (No model.)

To all whom it may concern:

Be it known that I, JOHN A. PEER, a citizen of the United States, residing at Washington, in the District of Columbia, have invented certain new and useful Improvements in Mills; and I do hereby declare the following to be a full, clear, and exact description of the invention, such as will enable others skilled in the art to which it appertains to make and use the same.

My invention is an improved mill; and it consists in the novel features of construction and combination of parts hereinafter described, reference being had to the accompanying drawings, which illustrate one form in which I have contemplated embodying my invention, and said invention is fully disclosed in the following description and claims.

Referring to the drawings, Figure 1 is a perspective view of a mill embodying my invention. Fig. 2 represents a vertical longitudinal section of the mill. Figs. 3 and 4 are details of parts of the construction. Fig. 5 is a view of the concave stationary cutting-disk. Fig. 6 is a similar view of the convex revolute cutting-disk. Fig. 7 is a vertical sectional view on line 7-7 of Fig. 2. Fig. 8 is an enlarged sectional view showing the operation of the rotary cutters in relation to the stationary knives and the serrated feeding-ring inclosing the same. Fig. 9 is a detail view of a portion of the concave stationary disk and convex rotary disk, showing one knife of each disk and illustrating the manner in which the inclined cutting edges of said knives co-operate. Fig. 10 represents a section on line 10-10 of Fig. 9. Fig. 11 is an elevation looking into the casing G with casing H removed. Fig. 12 is a detail view of the knife-plate and rotary knives. Fig. 13 is a view similar to Fig. 7, showing a slight modification of my invention. Fig. 14 is a detail perspective view of the annular serrated feeding-plate. Fig. 15 is a similar view of the stationary knife-plate and stationary knives.

The object of my invention is to produce a mill in which the material is continuously cut, split, and sheared from the time it enters the mill until it leaves it, becoming continuously finer and finer until it reaches the condition of an almost impalpable powder; and to this end it involves the novel features

of construction hereinafter described. The parts of my mill which perform this cutting, splitting, and shearing action do not come in contact with each other, so that there is comparatively little friction, and the mill can be run at an extremely high speed, and I also provide means for directly cooling the material operated upon to prevent any danger of injuriously heating the same.

Referring to the drawings, A represents the main body or casing of my improved mill, which is provided on one side with a circular recess a, in the bottom of which is formed the concave stationary cutting plate or disk A', which may be cast or formed integrally with the main casing, as indicated in the drawings, or may be formed separately and secured thereto, if preferred.

B represents a bracket which is preferably formed separate from the casing A and bolted or otherwise secured thereto and is provided with two bearings b for the horizontal shaft b', the said bracket B and casing A being supported upon a bed or stand C or any other suitable support. The shaft b' is provided between its bearings with a band-wheel b², and said shaft extends to an opening in the casing A concentric with the stationary cutting-plate and is provided within the casing A with a revolving convex cutting disk or plate B', which is secured to and revolved with the shaft b'. The inner end of the shaft b' is tapered, as shown in Fig. 2, and the revolving plate or disk B' is provided with a similarly-shaped aperture therethrough, which fits tightly upon the tapered portion of the shaft.

B² represents a knife-plate which preferably engages a recess extending diametrically across the flat rear face of the rotary cutting-disk, said plate being provided with a central aperture, through which the shaft b' passes. The extreme end of the shaft is provided with a threaded portion, a nut, and washer, by means of which the knife-plate B² is secured to the disk B', and both are firmly united to the shaft b' and made to turn therewith. The knife-plate B² is provided at each end with a series of knives b⁷, hereinafter described, and I prefer to form these knives integral with the knife-plate B² and secure the knife-plate to the rotary disk in the manner

described, this being a very simple, cheap, and effective construction. It is obvious, however, that these knives might be made separate from each other and separately attached 5 to the rear face of the rotary disk by other means.

In Fig. 5 I have illustrated a view of the stationary cutting disk or plate as it would appear looking directly into it after removing 10 the rotary cutting-disk. This stationary disk A' is concave, as heretofore described, and is provided with several rows of cutting-knives a³, concentric with each other and the disk, the knives of each row being separated by intervals and the knives of each row being located opposite the intervals between the knives of the adjacent rows. All of these knives are of substantially the same construction, although they differ somewhat in size 15 20 and length according to their different positions upon the concave surface of the disk, the knives nearest the center of the plate being coarser and of less length than those nearer the periphery of the disk. Each of 25 these knives is triangular in cross-section and is provided at one end with a face a⁴, inclined to the longitudinal axis of the knife. This inclined face forms an acute angle with the inner lateral face of the knife, forming an elongated backwardly-inclined cutting edge a⁵, and said face a⁴ forms an obtuse angle with the outer lateral face of the knife, forming an edge a^x substantially perpendicular with the plate or disk A'. The said inclined faces 30 35 a⁴ thus extend from the cutting edges of the knives outwardly and tend to move the material toward the periphery of the disk or plate A' as it is cut. The inclined cutting edges a⁵ are located at the same ends relatively of all the knives, as indicated in Fig. 40 45 50 55 60 65 70 75 80 85 90 95 100 105 110 115 120 125 130 135 140 145 150 155 160 construction shown in detail in Figs. 3 and 4. In these figures, D represents a yoke which is secured to the bracket B adjacent to the outer bearing b of the shaft b', and within 5 said yoke is a slide d, having guiding-flanges d' at each side, which engage a guiding-rib d² on each side of the yoke. The shaft b' is provided near its outer end with an annular groove b⁶. d⁸ d⁹ represent the two halves of 10 a split collar, which surround the end of the shaft b' and are held within the slide d by screws d⁴ d⁴. The halves of the split collar are provided each with a semi-annular rib or web d⁵, which projects into the annular groove 15 or recess b⁶ in the shaft, thus securing the slide d to the shaft, but permitting the revolution of the shaft. d⁶ represents an adjusting-shaft having a headed portion d⁷ within the slide d, the said adjusting-shaft having 20 a threaded portion which extends loosely through an unthreaded aperture in the end of the yoke D and is provided with an adjusting-nut d⁸, preferably in the form of a hand-wheel, as shown, having a central threaded 25 aperture engaging the screw-threaded shaft d⁶, and a jam-nut d⁹ of the same form. In order to allow the revolving disk B' to move away from the stationary disk in case any refractory material is introduced into the 30 mill which would be liable to injure the parts thereof, such as pieces of iron or steel, I prefer to interpose a spring d¹⁰ between the shaft b' and its adjusting devices. In Fig. 3 I have shown this spring interposed between the nut 35 d⁸ and the end of the yoke; but it may be used in other ways to produce the same result. I also prefer to provide a washer d¹¹ (see Figs. 2 and 3) between the end of the shaft and the head of the adjusting-shaft d⁶ 40 for the purpose of preventing the rotation of the shaft from accidentally operating the adjusting-shaft or wearing the head of the same.

As previously described, the rear face of the 45 rotary disk is provided with a diametrically opposite series of knives b⁷, which in this instance are formed integrally with the knife-plate B², the said knives being set at a sharp angle to the radius of the disk and parallel to each other and provided with sharp cutting 50 edges b⁸ and inclined guiding-faces b⁹, extending inwardly therefrom. The casing A is provided with a ring E adjacent to the rear face of the disk B', which ring is provided with a series of serrations forming inclined 55 projections e, adjacent to the points of which the knives b⁷ travel, as will be clearly seen in Figs. 7 and 8. The projections e of the ring E are provided with long inclined faces e', extending in a direction opposite to that of the knives b⁷, and deep recesses e² are formed 60 between the projections, into which the material passes from the disks A' B'. The material which enters the recesses e² is forced by the direction of rotation of the disk B' to travel 65 along the inclined faces e' of the projections which carry it inwardly to a point where it is cut and split and sheared by the knives b⁷,

and on account of this action of the said projections in feeding the material inward to the knives I prefer to term this plate the "serrated feeding-plate." I also provide a series of cutting-knives on the inner side of the path of the rotary knives, which stationary knives f are arranged concentrically to the axis of rotation of the rotary knives. In the present 70 instance I have shown an annular stationary knife-plate F, which is secured to the casing A and provided with a circular series of the stationary knives f, projecting into the recess a of the casing A, and provided with cutting edges f', extending in a direction opposite to the direction of rotation of the rotary knives, (see particularly Figs. 7 and 8,) and inclined inwardly-extending guiding-faces f². The knives f are preferably made diamond shape 80 in cross-section, and their outer edges or faces are so close to the path of the rotary knives that the rotary knives almost touch them in passing. Referring to Figs. 7 and 8, the action of the rotary knives in conjunction with the serrated feeding-plate and the stationary knives f will be apparent. The material operated upon, which has been brought to a finely-divided condition by the knives of the cutting-disks A' B', will be forced outwardly 85 by centrifugal force and will find its way to the recesses e² of the serrated feeding-plate E. The circular action of the rotary knives will cause said material to pass along the inclined surfaces e' of the projections e to the 90 points of said projections, where it will be acted upon by the cutting edges of the knives b⁷ b⁷ and cut, split, and sheared into still finer particles. The material will then pass along the inclined guiding-faces b⁸ of the knives b⁷ toward the axis of rotation of said knives and will thus be brought into the field of operation of the cutting edges f' of the stationary knives f, which will still further cut, split, 95 and shear the material, which passes inwardly along the guiding-faces f² in the condition of an almost impalpable powder. 100

The recess a of the casing A opens into a casing G, which extends in this instance a considerable distance above the casing A. I 115 find it convenient to form the casings A and G in a single casting; but the casing G may be formed separately and secured to the casing A, if desired. The casing G is open on its outer side and communicates with a similar casing H, which is preferably hinged thereto at one side and secured to its other side by means of a bolt g, pivoted to the casing G at g', engaging a slotted lug h on the casing H and provided with a wing-nut g², as clearly shown in Fig. 1. The casing H is also provided on its outer face with a door h', hinged to the casing and secured at its opposite edge by a pivoted bolt h², engaging a slotted lug h³ of the door and provided with 120 a wing-nut h⁴, so that access may be had to the interior of the casing H when desired. Between the casings H and G is interposed a removable screen I, which is preferably 125

clamped along the edges between the meeting faces of the two casings, so that by loosening the nut g^3 , disengaging the bolt g from the slotted lug h , and swinging the casing H 5 on its hinges away from the casing G the screen I may be removed and another screen of larger or smaller mesh can be readily inserted. The casing H is provided with a horizontal air-tube h^5 , which is concentric with the shaft b' and extends inwardly through the casing G to a point adjacent to the inner end of the shaft b' , as shown in dotted lines in Fig. 2, in which figure the tube h^5 is broken away for the clearer showing of the stationary knives f . The air-tube h^5 is provided with one or more screens h^6 to prevent the admission of any foreign matter with the air into the interior of the mill. The said air-tube necessarily passes through the screen I , 10 and in order to hold said screen firmly around the air-tube I find it convenient to provide the exterior of the air-tube with screw-threads, as indicated in Fig. 2, and to employ a pair of threaded clamping-rings h^7 h^7 , between 15 which the edges of the screen are clamped.

The casing G is provided at its upper end with an opening g^8 , which communicates with an outlet-tube g^4 , provided with a cut-off slide or valve g^5 for closing or regulating the outlet at this point. The casing H is provided at its lower end with a discharge-outlet h^8 . The rear face of the rotating cutting-disk B' is provided with two or more fan-blades K , (see Figs. 2 and 7,) which draw air inward 30 through the air-tube h^5 and force it into the casing G .

L represents a feeding-hopper communicating by a tube l with the stationary and revolving cutting-disk and adapted to deliver thereto the material to be operated upon. This tube l is provided with a cut-off slide or valve l' for the purpose of regulating the feed of the material to the mill.

The operation of the mill is as follows: The material is placed in the hopper L , passes 45 down the tube l , and between the stationary and revolving disks A' B' , where it is operated upon by the inclined cutting edges a^5 b^5 of the teeth of said disks, and is cut, split, and sheared into small particles and at the same time fed 50 by centrifugal force toward the periphery of the revolving disk. The material passes around the periphery of the disk to the serrated feeding-plate E and is then acted upon by the rotary knives b^7 b^7 and stationary knives f , as has been heretofore minutely described with reference to Figs. 7 and 8. The fan-blades K draw air into the air-tube h^5 , which mingles with the finely-divided material, and when the slide or valve g^5 at the top 55 of the casing G is closed the air laden with the finely-divided particles is blown by the fan through the screen I into the casing H and out through the discharge-aperture h^8 . The material, which is sufficiently fine to pass 60 through the screen I , will pass into the cham-

ber H and be discharged at the bottom through the outlet h^8 into a suitable receptacle. If any of the particles are of such size that they will not pass through the screen I , they will fall to the bottom of the casing G and will be drawn into the field of operation of the rotary knives b^7 and stationary knives f and again subjected to the cutting action thereof, so as to be further reduced. By regulating the size of the mesh of the screen I the fineness of the material discharged can be controlled. The current of air passing through the tube h^5 into the interior of the mill and being discharged therein against the rear face of the revolving disk serves to 70 keep the material operated upon cool, and I have found by experiment that even when running at a speed of five thousand revolutions per minute and above that speed and operating upon very refractory substances material 75 will remain cool and there is no danger of any injurious heating of the same. With my improved mill it is possible to grind widely-different materials, such as rags, paper, vegetable fibers, grains of all kinds, rock, and ores, 80 including even the refractory gold-containing quartz, which I have successfully operated upon with my improved mill. Owing to the fact that the revolving parts of the mill do not come into contact with the stationary 85 parts, but rely solely upon the cutting action throughout, there is very little friction in running the mill, and the wear coming upon the cutting edges, which are all self-sharpening on account of their peculiar construction, even the most refractory material can 90 be reduced without perceptibly affecting the cutting edges. By reference to Figs. 7 and 8 it will be seen that the cutting edges of the revolving and stationary knives are 95 formed by the meeting of two plane faces at an acute angle in the same manner that the cutting edges of the diamond-shaped knives of the disks A' and B' are formed. By virtue of this construction any wear upon these 100 parts will tend to keep the cutting edges always sharp, or, in other words, all the cutting edges of my improved mill are self-sharpening.

In operating upon the different grains it 115 may be desirable in some instances to remove the bran, so that it shall not form a part of the product. To do this, it is only necessary to open the slide g^5 at the top of the casing G a regulated amount, so as to allow part of the 120 air-current created by the fan-blades K to pass out through the exit-pipe g^4 . The bran being lighter than the starchy particles of the grain will be wafted to the top of the casing B and not being able to pass through the 125 screen will be blown out through the pipe g^4 , while the flour particles will pass through the screen and be discharged through the aperture h^8 . If it is desirable to grind the entire grain, the valve g^5 will be closed, and the 130 bran will then be confined within the casing G and continually returned to the action of

the cutting-knives until it has been reduced to such fineness that it will pass through the meshes of the screen I.

It is not absolutely essential that the separated feeding-plates should extend entirely around the path of the rotary knives, as shown in Figs. 2 and 7, and it is not necessary that the series of stationary knives *f* should be an annular series. I have found 10 that good results can be obtained, especially in the smaller sizes of my mill, by employing a semi-annular feeding-plate *E* and a semi-annular series of stationary knives *f*, as illustrated in Fig. 13, in which the parts of my 15 mill shown are identical with those previously described except in these particulars.

For convenience of reference I term the space inclosed by casings *G* and *H* the "screening-chamber," which is provided with the upper 20 discharge-aperture *g*⁸ on the side of the screen nearest the revoluble disk and the lower discharge *h*⁸ on the opposite side of the screen.

What I claim, and desire to secure by Letters Patent, is—

1. In a mill, the combination with means for effecting a preliminary reduction of the material, of a curved feeding-plate having its inner face provided with a series of projections, and recesses between said projections, and a rotary knife traveling in a path concentric with said feeding-plate and provided with a straight shearing edge adapted to pass close to but without touching said projections of the feeding-plate, substantially as described.

2. In a mill, the combination with means for effecting a preliminary reduction of the material, of a curved feeding-plate having its inner face provided with a series of transversely-extending projections provided with feeding-faces, and transversely-extending recesses between said projections, and a rotary knife traveling in a path concentric with said feeding-plate and having a straight shearing edge adapted to pass close to but without touching the projections of said feeding-plate, whereby the material is fed along the feeding-faces of said projections toward the path 45 of said knife, substantially as described.

3. In a mill, the combination with means for effecting a preliminary reduction of the material, of a curved feeding-plate provided with a series of projections extending transversely thereof, a series of stationary knives arranged concentric with and parallel to the inner face of the said feeding-plate, and a revolving knife, adapted to pass between said feeding-plate and said stationary knives without 55 touching the same, substantially as described.

4. In a mill, the combination with means for effecting a preliminary reduction of the material, of a curved feeding-plate, provided 65 with a series of transversely-extending projections, a rotary knife traveling in a path concentric with said feeding-plate and adapt-

ed to pass close to, but without touching the projections thereof, and a series of stationary knives arranged in a curved line concentric 70 with the path of the rotary knife, and between said knife and its axis of rotation, the said rotary knife having projections passing close to but without touching the edges of said stationary knives, substantially as described.

5. In a mill, the combination with the stationary and revoluble cutting-disks, of the circular feeding-plate adjacent the periphery of the rotating disk and concentric therewith, provided on its inner face with projections having inclined surfaces and recesses between said projections, a circular series of stationary knives concentric with the inner face of said feeding-plate, and having their 80 cutting portions extending in a direction opposite to the inclined portions of the said projections and a rotary knife adapted to pass between the said projections of the feeding-plate and said stationary knives, substantially 85 as described.

6. In a mill, the combination with the cutting-disks one of which is revoluble with respect to the other, said disks being each provided with circular rows of knives having 95 cutting edges and adapted to lie between adjacent rows of knives on the other disk, of the serrated feeding-plate, a series of stationary knives arranged concentric with the serrated face of said plate and a revolving knife 100 carried by the revoluble disk and adapted to pass between said stationary knives and the serrated face of said feeding-plate, substantially as described.

7. In a mill, the combination with means for effecting a preliminary cutting of the material, of a curved feeding-plate provided with inwardly-extending projections provided with inclined faces, and recesses between said projections, a curved series of stationary 105 knives arranged concentric with said projections, said knives having cutting edges and inclined guiding-surfaces extending inwardly therefrom and a rotary knife adapted to pass between said projections and said stationary 110 knives, provided with a cutting edge and an inclined guiding-face extending from said edge inwardly for guiding the material to the cutting edges of the stationary knives, substantially as described.

8. In a mill, the combination with the main casing and the knife-carrying cutting-disks one of which is revoluble with respect to the other, of the serrated feeding-plate concentric with the revoluble disk, a series of stationary knives arranged concentric with the serrated plate, a revoluble knife carried by said revoluble disk adapted to pass between said serrated feeding-plate and the stationary 125 knives, a screening-chamber communicating with said casing, and provided with a vertical screen having its lower end adjacent to the lower portions of said feeding-plate and stationary knives, said screening-chamber being 130

provided with a discharge-aperture, an air-inlet for the screening-chamber discharging at a point adjacent to the revolute disk and fan-blades carried by said revolute disk, substantially as described.

9. In a mill, the combination with the main casing and the knife-carrying cutting-disks, one of which is revolute with respect to the other, of the serrated feeding-plate concentric with the revolute disk, a series of stationary knives arranged concentric with the serrated plate, a revolute knife carried by said revolute disk adapted to pass between said serrated feeding-plate and the stationary knives, a screening-chamber communicating with said casing, and provided with a vertical screen having its lower end adjacent to the lower portions of said feeding-plate, and sta-

tionary knives, said screening-chamber being provided with a discharge-aperture in the top 20 thereof on the side of the screen nearest the revolute disk, and a discharge-aperture on the other side of the screen, adjacent to the bottom of the chamber, a valve for regulating or closing the upper discharge-aperture, an 25 air-inlet for said chamber discharging adjacent to the revolute disk and fan-blades carried by said revolute disk, substantially as described.

In testimony whereof I affix my signature 30 in the presence of two witnesses.

JOHN A. PEER.
